(57) **CLAIM**

The ornamental design for a handle for a closure element, as shown and described.

DESCRIPTION

FIG. 1 is a side, bottom and front perspective view of our design for a handle for a closure element;

FIG. 2 is an elevation view from the same side as in FIG. 1; FIG. 3 is an elevation view from the side opposite that in FIG. 2;

FIG. 4 is a rear elevation view;

FIG. 5 is a front elevation view;

FIG. 6 is a top view; and,

FIG. 7 is a bottom view.

The portion of the handle for a closure element shown in dotted lines in FIGS. 1-7 does not constitute a part of the claimed design.
